HERBERT C. TAYLOR, OF GREENSBURG, INDIANA.

ADJUSTABLE OVEN.

1,109,263.

Specification of Letters Patent.

Patented Sept. 1, 1914.

Application filed January 22, 1912. Serial No. 672,615.

To all whom it may concern:

Be it known that I, HERBERT C. TAYLOR, a citizen of the United States, and a resident of Greensburg, county of Decatur, and State 5 of Indiana, have invented a certain useful Adjustable Oven; and I do hereby declare that the following is a full, clear, and exact description thereof, reference being had to the accompanying drawings.

10 The object of this invention is to combine an oven with a plurality of sources of heat, such as burners, stove holes or any other means for heating, and an adjustable partition or partitions in the oven so as to adapt 15 the oven for use with only one burner or source of heat or with two or more burners or sources of heat.

In the drawings herein a portable oven is shown in connection with a gas stove having 20 burners, but the invention is not limited to the portable oven nor to the gas stove. With this arrangement the oven chamber can be readily adjusted to suit the need at any particular time and thereby save the 25 heat or fuel and also afford other advantages. If one burner be used, the reduction of the size of the oven chamber will require less heat. If more than one burner be used and the oven chamber be limited to only 30 one of said burners, not only will there be a saving of heat and fuel but, if desired, the other burners can at the same time be used for other purposes such as for frying or heating water.

35 The nature of the invention will be understood from the accompanying drawings and the following description and claims:

In the drawings, Figure 1 is a perspective of my oven placed upon a hot plate. 40 Fig. 2 is a vertical mid-section longitudinally of the oven. Fig. 3 is a vertical transverse section on the line 3—3 of Fig. 2. Fig. 4 is a perspective of the flame spreader.

In detail there is shown in the drawings 45 an oven 10 suitable for a gas or oil stove and receiving heat from the burners of a stove 11. Said oven is formed of sheet metal after the well-known manner and with the usual drop door 12 provided with latches 13 for 50 securing it in closed position. The central portion of the bottom is cut away to allow the heat from the stove burners to pass upward into the oven. A heat deflector 14, hereinafter described, is placed midway between 55 the front and rear walls and deflects the heat from the burners toward the front

and rear walls. Insulating chambers 15 and 16, adjacent to the back and top, respectively, of the oven, provide a dead air or insulating space to reduce the radiation of 60 heat from the oven. Said chambers 15 and 16 are divided into three chambers by U-shaped partitions 115, see Fig. 2, for the purpose hereafter described.

There is an adjustable insulating or dead 65 air chamber 17 normally lying adjacent each end wall 18, which may be moved inwardly to reduce the distance therebetween, thereby reducing the active radiating surface of the oven. Said insulating chambers 17 are box- 70 like in form and have a sheet 19 of some poor heat conducting material, such as asbestos, within the same and on the side adjacent the interior of the oven. Said partition chambers 17 are supported by the bottom flange 40 of the oven and each partition has through it a triangular opening 20 through which the heat deflector 14 extends and whereby said heat deflector is supported. 75

The heat deflector 14 is formed of sheet 80 metal and is substantially an isosceles triangle in cross section and is supported in the openings in the chambers 17 with the base of the triangle upon the upper side and the 85 vertex adjacent the burner. In length said heat deflector is equal to the distance between the outer end walls 18 and the width of the base is substantially more than one half the depth of the oven. As heretofore 90 mentioned it is substantially midway between the front door and rear wall of the oven and leaves a passage upon either side to allow the deflected heat to rise into the oven above. There is a V-shaped cut in the 95 upper face 26 of the deflector near each end with the vertex toward the center of the oven and the tongue 22 of the metal thus formed is bent downward to close the passage through the deflector. Midway between its ends there are two transverse slits 23 in the upper face 26 through which the ends 24 of a U-shaped piece of metal extend and divide the interior of the deflector into two chambers with a dead air space between 100 them. The portion 25 between the projections 24 lies fairly flat on the upper face 26 of the deflector. Upon each side of said flat portion 25 a rectangular opening 27 is cut in the face 26 and the inclined lower sides 110 of said deflector 14 have perforations 28 to allow heat to enter the interior of the de-

80

flector and ascend through the openings 27 in the upper face 26 and the openings 29 left by the tongues 22.

When it is desired to use the oven for but a few dishes and these are of ordinary size, the oven racks are removed and one of the insulating members 17 is moved to the position shown in Fig. 1, after which short oven racks 30 are slid into place on the ribs 21 and the reduced portion of the oven may be placed over a single burner and heated by the same. The major portion of the heated gases arising will be deflected to the front and rear as usual, but a part will enter the interior of the deflector through the perforations 28 and pass out through the openings 27 and 29 adjacent the end walls and keep them heated. The short oven racks 30 are of such a length that the adjustable chamber 17 will be opposite one set of the partitions 115 and heat cannot escape behind or over the chamber 17 and the U-shaped partition in the heat deflector 14 will prevent an escape of heat from the heated to the unheated part of the oven through the heat deflector. The tongue 22 will prevent any passage of heat to the exterior end wall 18. Either of the members 17 may be adjusted and there are two U-shaped strips 32 of sheet metal secured to the inside face of the door 12, one of which will engage the front edge of the insulating member 17 and seal the front edge against a loss of heat depending upon which of said members has been moved inward. The usual perforations 33 and 34 are provided in the members 17 and the end walls 18, respectively, to promote a circulation of the heat within the oven. There is a ring 35 in each of said members 17 to assist in moving and adjusting the same.

By this invention the top of the stove may be used with greater efficiency, for with a stove with, say three burners, the ordinary oven of similar size when set on the top of the stove occupies space so that it is placed over two of the burners, but with this invention it will be possible to place the oven chamber toward one end or the other so that one burner is located directly under the part of the oven which it is desired to heat and have the other burners left for other uses; whereas in all the ordinary ovens of the size which occupies enough space to set over two burners of the ordinary three-burner stove, the space of two of the burners is covered in heating the oven for general cooking.

I claim as my invention:

1. A cooking oven having an open bottom, and a transverse partition for dividing the same into a plurality of chambers, said partition being adapted to remain in the oven and be slidable therein from one end to the other, so that one oven chamber

may be provided or a plurality of chambers of any desired dimensions.

2. The combination of an oven adapted to be heated by a plurality of heating means and a member loosely disposed within the oven and normally lying adjacent one wall thereof which may be adjusted to any position between the ends thereof for reducing the size of the heating chamber and the number of means necessary for heating the same.

3. The combination of an oven having an open bottom, a plurality of separate means for heating the same; and a non-conducting member loosely disposed in each end of the oven which may be adjusted to any position between the ends thereof, said members being normally positioned adjacent the outer end walls thereof.

4. The combination of an oven having an open bottom, a plurality of separate means for heating the same, and a non-conducting chamber loosely disposed within the oven and normally forming a part of one wall thereof which may be adjusted to any position between the ends thereof.

5. The combination with an oven having heat insulating means for reducing the radiation of heat from the oven, and a plurality of separate means for heating said oven, of a non-conducting chamber loosely disposed in each end of said oven which may be adjusted to any position between said heat insulating means whereby when of said oven, and means for sub-dividing the heated portion of said oven is reduced heat will be prevented from passing from said heated portion to the unheated portion of the oven.

6. The combination with an oven, a plurality of separate means for heating the same, and means for deflecting the heat toward the walls thereof, of a non-conducting chamber loosely disposed in each end of the oven and through which said heat deflecting means extends, said chambers being adjustable to any position between the ends thereof for reducing the heated space of said oven, and means for subdividing the interior of said heat deflecting means whereby heat will not be transmitted from the heated portion to the unheated portion of said oven through said heat deflecting means.

7. An oven, a plurality of heating means below the same, a heat deflector in the lower part of the oven and above the heating means and extending longitudinally of the oven and spaced from the front and rear walls thereof, and a vertical transverse partition in the oven slidable longitudinally from one end thereof to the other for adjustment and through which said heat deflector extends.

8. An oven, a plurality of heating means

below the same, a hollow heat deflector in the lower part of the oven and above the heating means and extending longitudinally of the oven and spaced from the front and rear walls thereof, a partition in said heat deflector located between each heat producing means, and a vertical transverse partition in the oven slidable longitudinally from one end thereof to the other for ad-

justment and through which said heat deflector extends.

In witness whereof, I have hereunto affixed my signature in the presence of the witnesses herein named.

HERBERT C. TAYLOR.

Correction in Letters Patent No. 1 109,263.

It is hereby certified that in Letters Patent No. 1,109,263, granted September 1, 1914, upon the application of Herbert C. Taylor, of Greensburg, Indiana, for an improvement in "Adjustable Ovens," an error appears in the printed specification requiring correction as follows: Page 2, strike out lines 92-104, comprising claim 5, and insert the following:

5. The combination with an oven having heat insulating means for reducing the radiation of heat from the oven, and a plurality of separate means for heating said oven, of a non-conducting chamber loosely disposed in each end of said oven which may be adjusted to any position between the ends thereof, and means for subdividing said heat insulating means whereby when the heated portion of said oven is reduced heat will be prevented from passing from said heated portion to the unheated portion of the oven.;

and that the said Letters Patent should be read with this correction therein that the same may conform to the record of the case in the Patent Office.

Signed and sealed this 9th day of February, A. D., 1915.

[SEAL.]

J. T. NEWTON,

Acting Commissioner of Patents.
